(57) **CLAIM**

The ornamental design for a hose reel, substantially as shown and described.

DESCRIPTION

FIG. 1 is a perspective view, taken from the top, left and front of the hose reel showing our new design;

FIG. 2 is a front elevational view of the design of FIG. 1;

FIG. 3 is a left side view of the design of FIG. 2;

FIG. 4 is a top view of the design of FIG. 2;

FIG. 5 is a rear elevational view of the design of FIG. 2;

FIG. 6 is a right side view of the design of FIG. 2;

FIG. 7 is an enlarged sectional view through the sight line 7—7 of FIG. 5; and,

FIG. 8 is an enlarged sectional view through the sight line 8—8 of FIG. 5.

The broken lines showing environment in the drawing are for illustrative purposes only and form no part of the claimed design.
